[57] CLAIM

The ornamental design for a turntable for record player, substantially as shown and described.

DESCRIPTION

FIG. 1 is a top and left side perspective view of a turntable for a record player showing my new design; FIG. 2 is a partial front, top and partial left side perspective view;

FIG. 3 is a top plan view; and

FIG. 4 is a sectional view taken along lines 4—4 of FIG. 2.

The overhanging lip and the control housing of the turntable are symmetrical and plain, except for the control knobs and indicator window, the latter being transparent. The control housing base is cylindrical.
